UNITED STATES PATENT OFFICE.

EDWARD A. MORLEY, OF LEE, MASSACHUSETTS.

UNIVERSAL ELECTRIC DAMPER AND FIRE-ALARM.

SPECIFICATION forming part of Letters Patent No. 350,548, dated October 12, 1886.

Application filed February 8, 1886. Serial No. 191,249. (No model.)

To all whom it may concern:

Be it known that I, EDWARD A. MORLEY, a citizen of the United States, residing at Lee, in the county of Berkshire and State of Massachusetts, have invented a new and useful Universal Electric Damper and Fire-Alarm, of which the following is a specification.

My invention relates to electric dampers, and has for its object to provide means for automatically regulating the temperature of rooms, hot-houses, incubators, and other inclosures wherein it is necessary or desirable that an even temperature be maintained.

The invention involves, primarily, the principles of the expansion of metals by heat, the electric current, and the electro-magnet; and the invention consists in the devices and their arrangement for accomplishing the object stated, as will be hereinafter more fully set forth.

In the accompanying drawings, Figure 1 illustrates the parts and their arrangement in accordance with my invention; Fig. 2, the damper. Fig. 3 is a top view of the dial-plate, an adjustable screw, and indicating finger or pointer.

The apparatus A consists of the plate a, having upon its under side a suitable block or extension, b, of wood or other good non-conductor of electricity. The plate a is provided with a suitable opening, c', through which extends a strip or rod of copper, brass, or other good expander by heat. The strip or rod c is secured at its lower end to the lower end of the block b, and at its upper end to a stiff spring, d, which will keep the said rod or strip distended, and at the same time freely permit its expansion and contraction. This spring d is insulatedly secured upon the bed 35 or plate a by means of a set-screw, e, passing through a bushing, e', of suitable insulating material. Upon the upper side of the plate a is mounted upon suitable posts or standards the under plate, f, provided with suitable 40 marks of graduation, and through a suitable bushing, f', is passed an adjustable screw, g, having its lower end in the line of the expanding rod or strip c'. The upper end of this adjustable screw is provided with an index finger or pointer, and the different degrees to which it is desired the temperature

should rise may be determined by different adjustments of the screw, the respective degrees being indicated by the finger or pointer upon the dial-plate.

In the apparatus for operating the damper (indicated by the letter B) the letter h indicates a suitable frame, in which is insulatedly secured the electro-magnets i, having cores i', and pivoted in this frame upon suitable bearings, j, j, is an arbor, k, carrying a lever, l, and an armature, m. The arbor k is mounted in the frame, so that the armature will oscillate in the plane of the cores i' and be attracted by said cores when the magnet is energized. 55 The lower end of the lever is provided with a damper, n, adapted to cover an opening leading to the outer air. The upper end of the lever may be provided with an adjustable balancing-weight, o, whereby the lever l may be 60 nicely balanced and operated readily by the action of the electro-magnets. The bearings are such as to permit the easy movement of the arbor. Conductors of electricity, p and p', having their terminals connected with a suitable galvanic battery, q, are connected with the coils. The apparatus A is interposed in one of these conductors, p', one end being connected to a binding-post, r, on the plate a, and the other to the binding-post r', in electrical 65 contact with the spring d. 70

The operation is as follows: The screw g is adjusted so that its lower end is the proper distance from the outer end of the spring d. Now, when the heat becomes so high as to expand the strip or rod c' until the spring d comes into contact with the lower end of the screw g, the circuit between p and p' will be completed through the battery q, post r', spring d, screw g, the dial-plate and its standards or supports, plate a, binding-post r, thus energizing the electro-magnets i, which will attract the ends of the armature m, causing the lever l to oscillate and remove the damper n from the opening, admitting fresh air. When the air in the inclosure has sufficiently cooled, the strip or rod c' will contract, thus breaking the circuit and demagnetizing the cores i', when the damper n will fall, again closing the opening.

The damper n may be made funnel-shaped and opened at its upper side and provided

with a small opening at its apex, to permit the exit of the water of condensation, which would otherwise make that end too heavy, and thus interfere with the proper operation of the apparatus.

The plate *a* may be provided with suitable screws for securing it in a portion of the apparatus or room upon or in which it is to be used.

Having thus described my invention, what I claim, and desire to secure by Letters Patent, is—

1. In an apparatus, substantially as described, for regulating the temperature of rooms and other inclosures, the plate or frame *a*, provided at one side with the extension *b* and the expanding rod *c*, combined with the dial-plate and an adjustable screw passing therethrough, having its lower end in the line

of expansion of the rod *c*, and the upper end 25 provided with an index-finger, substantially as and for the purposes set forth.

2. In an apparatus for regulating the temperature of inclosures, substantially as described, the combination of the frame *h*, electro-magnets secured therein, the arbor *k*, provided with oscillating armature and lever journaled in said frame, the said lever being provided with the damper *n*, adapted, upon magnetizing and demagnetizing the electro-magnets, to open and close an opening for the admission of fresh air, substantially as set forth.

EDWARD A. MORLEY.
